Specification for Design.

Patented Apr. 25, 1922.

Application filed October 22, 1921. Serial No. 509,747. Term of patent 7 years.

To all whom it may concern:

Be it known that I, EDWARD E. GRAY, a citizen of the United States, residing at Plano, in the county of Kendall and State of Illinois, have invented a new, original, and ornamental Design for an Emblem, Badge, Button, or Article of Similar Nature, of which the following is a specification, reference being had to the accompanying drawing, forming a part thereof.

The attached drawing is a face view of an emblem, badge, button and article of similar nature made in accordance with my design.

I claim:

The ornamental design for an emblem, badge, button, or article of similar nature as shown.

In witness whereof, I have hereunto subscribed my name.

EDWARD E. GRAY.
